SUPPORT FOR BEDCLOTHES

Henrietta Uhl, 151 8th Ave., New York, N.Y.
Filed Dec. 22, 1960, Ser. No. 77,571
9 Claims. (Cl. 5—319)

The present invention is directed to a device adapted to be applied to a bed for the purpose of supporting the bed clothes above the feet of the occupant in order to avoid undue pressure on the feet.

A considerable number of devices of this type have previously been proposed, some of which are operative for accomplishing the purpose. However, most of them are quite complicated in the construction thereof and are inconvenient to use. Others which are less complicated have other defects such as the bulkiness of the device, the difficulty in adjusting the same to the bed and retaining them in position, and they also have the defect that they cannot be stored in a confined space when not in use.

The present invention is intended and adapted to overcome the difficulties and disadvantages inherent in prior devices of the type described, it being among the objects thereof to provide a support for bed clothes which is simple in construction, inexpensive and effective in use.

It is also among the objects of the present invention to provide a device of the character described, which can be easily and readily installed in a bed, which may readily be removed and which is adapted to be stored in a very small space and particularly in the bed itself.

In practicing the present invention, there is provided a strip of relatively stiff material, usually a plastic strip which has some flexibility, the length of the strip being about that of the width of the bed. The strip is placed under the mattress at the foot of the bed and constitutes the base for the supporting elements. The supporting member is of relatively stiff material and usually of a synthetic plastic having considerable elasticity and the length of which is greater than that of the strip. Means are provided whereby the ends of the sheet may be interlocked into the ends of the strip so that the supporting member assumes a bow shape. The bed clothes are supported by the bowed sheet to avoid pressure of the bed clothes on the feet of the occupant of the bed.

In a preferred form of the invention, the sheet is made in two parts, hinged or otherwise held together so that when not in use the parts of the sheet which now assume a flat form, may be folded together and the length of each piece being not greater than the width of the bed, the folded sheet may now be slipped under the mattress or under the bed spread without occupying any substantial amount of space and without detracting from the appearance of the bed when it is made up.

The invention is more fully described in connection with the accompanying drawing constituting a part thereof, and in which like reference characters indicate like parts, and wherein—

FIG. 1 is a longitudinal cross-sectional view taken through the strip constituting the base and showing the bowed sheet in position;

FIG. 2 is a top plan view of said strip;

FIG. 3 is a side elevational view of the sheet folded and ready for storage;

FIG. 4 is a fragmentary plan view of one end of a sheet showing a modified form of the invention;

FIG. 5 is a view similar to FIG. 4 of a modified form of base, cooperating with the sheet of FIG. 4;

FIG. 6 is an elevational view of a modified form of sheet wherein the hinge of FIG. 1 is replaced by a different mechanism, and

FIG. 7 is a longitudinal cross-sectional view of a further modification of a strip or base member and included in the present invention.

2

Referring to the form of invention shown in FIGS. 1 to 3, there is provided a flat strip 1 of synthetic plastic material having openings 2 and 3 adjacent the ends thereof. At the inner edges of openings 2 and 3 are upstanding lips 4 and 5, respectively. Strip 1 is placed under mattress 6 in order that it be held firmly in position against accidental displacement. Lips 4 and 5 engage the sides of the mattress whereby strip 1 is held firmly in position.

The bowed element consists of a pair of sheets 7 and 8, each of which is of a length greater than half the width of the bed. They are made of synthetic plastic material and they are joined together by a flexible fabric or other element 9 which is cemented to the adjacent ends of sheets 7 and 8 by cementing or other suitable means. The extreme ends of the bowed element so formed are provided with tongues 10 and 11, respectively, the length of the tongues being such as to enable them to pass through openings 2 and 3 to engage the underside of strip 1. Lips 4 and 5 retain the bowed element in position.

When the device is not in use, the ends of sheets 7 and 8 are withdrawn from openings 2 and 3 whereby they straighten or flatten out and the sheets are folded together about hinge 9, as shown in FIG. 3.

In FIGS. 4 and 5, base 1' is provided with an opening 2' at each end and sheet 7' is provided with a tongue 12 of a width approximately equal to the width of opening 2', so that shoulder 13 will act as a stop against the possibility of sheet 7' being inserted too far into strip 1'. The corresponding end of the other sheet (not shown) is similarly provided with a tongue and shoulder for the same purpose.

With reference to FIG. 6, the hinge 9 of FIG. 1 may be replaced by other means. Sheets 7' and 8' are provided with tongues 10' and 11' similar to tongues 10 and 11 of FIG. 1. One of the sheets 7' is provided with a tongue 14 at the end adjacent to sheet 8', the latter having an opening 15 into which tongue 14 is inserted. In use the tongue is inserted into the opening and the ends of sheets 7' and 8' are introduced into openings 2 and 3 with tongues 10' and 11' fitting against the underside of strip 1.

In FIG. 1 is shown a somewhat different form of base element, which consists of a pair of relatively short strips 16 and 17. The ends thereof have openings 18 and 19 therein for the insertion of the bowed element and lips 4' and 5' are formed at the edges thereof. A flexible cord or the like 20 has its ends attached by suitable means as by the pins or the like, to the inner ends of strips 16 and 17. In this form of the invention, the storage of the device is simplified in that strips 16 and 17 may be stored alongside of each other or on top of each other in a smaller space than strip 1.

Although the invention has been described setting forth several specific embodiments thereof, the invention is not to be limited thereby as the several forms have been described for the purpose of indicating a considerable number of variations which may be made within the scope of the invention. For instance, sheets 7 and 8 may be replaced by a single sheet of synthetic plastic material. The lips 4 and 5 or tongues or flanges 10 and 11 may be omitted, if desired. Any suitable materials of construction may be used such as metal, fibrous material and others, provided that they have the characteristics necessary for accomplishing the results set forth above. The ends of sheets 7 or 8 may be notched so that the pressure of said ends on strip 1 will hold the sheets firmly.

The invention is not limited to use at the foot only of the bed. It may be placed any where under the mattress or under the bedspring to cover any part of the body. In the case of a patient suffering from injury to various parts of the body, such as severe burns, several of the supports may be used; in some instances the invention may hold the bed clothes from contact with any part of the body.

These and other changes in the details may be made within the spirit of the invention, which is to be broadly construed and not to be limited except by the character of the claims appended hereto.

I claim:

1. A support for bed clothes adapted to be associated with the mattress of a bed comprising an elongated strip of relatively stiff material of a length about equal to the width of said bed and constituting a base, an elongated sheet of relatively stiff and flexible material of a length greater than that of said strip and constituting a bow, said sheet being separate from said strip, cooperating means at the respective ends of said strip and sheet for detachably anchoring the ends of said sheet to hold said sheet in bowed position.

2. A support according to claim 1 characterized in that the ends of said strip have openings into which the corresponding ends of said sheet fit.

3. A support according to claim 2 characterized in that the ends of said sheet are provided with outwardly extending flanges.

4. A support according to claim 2 characterized in that the inner edges of said opening have upstanding lips adapted to be contacted by said sheet.

5. A support according to claim 2 characterized in that the width of said openings is less than the width of the ends of said sheet, and tongues on said ends fit into said openings.

6. A support according to claim 1 characterized in that said base has the ends thereof of said stiff material, and a flexible element connecting the inner faces of said ends.

7. A support according to claim 1 characterized in that said sheet is divided into two parts at a central area, and means for joining them are provided.

8. A support according to claim 1 characterized in that said sheet is divided into two parts at a central area, and a tape hinge for joining them are provided.

9. A support according to claim 1 characterized in that said sheet is divided into two parts at a central area, and interlocking elements on the inner faces of said parts for joining them are provided.
